UNITED STATES PATENT OFFICE.

WARREN H. TAYLOR, OF STAMFORD, CONNECTICUT.

DEVICE FOR DISINFECTING TELEPHONES, &c.

SPECIFICATION forming part of Letters Patent No. 643,309, dated February 13, 1900.

Application filed March 9, 1899. Serial No. 708,344. (No model.)

To all whom it may concern:

Be it known that I, WARREN H. TAYLOR, a citizen of the United States, and a resident of Stamford, in the county of Fairfield and 5 State of Connecticut, have invented new and useful Improvements in Devices for Disinfecting Telephones and other Similar Instruments, of which the following is a specification.

The present invention comprises a cap or 10 cover for a tubular mouth or ear piece of a speaking instrument having a hollow resili- enthandle projecting from the top of the same and a nose-piece or holder containing a disinfectant material, such nose-piece projecting 15 from the under side of said cover. The inner end of the handle opens into the nose-piece or holder, whereby a current of air is passed through the disinfecting material in the act of grasping the handle to remove the cap, 20 thereby carrying or forcing the disinfectant into the mouthpiece of the telephone or other speaking instrument, thus keeping it clean and wholesome.

In the drawings, Figure 1 is a perspective 25 view of a telephone with my attachment in place. Fig. 2 is a central vertical section through the attachment. Fig. 3 is a bottom plan view of the nose-piece of the same. Fig. 4 represents a tablet or lozenge of disinfect- 30 ing material. Fig. 5 is a vertical central section of a modified form of cap secured to the mouthpiece of a telephone, said mouthpiece being broken away. Fig. 6 is a similar view of another form of my invention. Fig. 7 is a 35 vertical central section of the construction shown in Fig. 6 detached from the telephone- mouthpiece and open.

1 represents a telephone-cabinet of im- 40 proved construction, and 2 the tubular mouth- piece of the same.

3 is the cap or cover, adapted to fit snugly over the outer end of the mouthpiece, whereby dust and other foreign matter are excluded from said mouthpiece. Said cap or cover is 45 provided with a central annular depression 4, in the center of which is formed an opening 5. 6 is one member of a bayonet-joint formed around said depression 4.

7 is a hollow bulb forming a handle for re- 50 moving or replacing the cover on the mouth- piece. The inner end of the bulb is provided

with a neck 8, which fits snugly and air-tight within the opening 5, formed in the annular depression 4.

9 is a hollow nose-piece or holder which is 55 provided with narrow slots 10 or other perforations and contains an absorbent cotton fiber 11, with a tablet or lozenge 12 of disinfectant material of an antiseptic nature, which has sufficient aromatic properties to cause it 60 to saturate any air that may pass through or over it. This may consist of formaldehyde, formalin, carbolic acid, wood-alcohol, camphor, ammonia, and carbids, the formation of which will produce a tablet which will air- 65 slack or vaporize by subjecting it to a current of air. The nose-piece is provided with one member of a bayonet-joint, adapted to interlock with the other member of the joint formed on the annular depression 4 on the cap or 70 cover, whereby said nose-piece is removably attached to said cover. Of course it is obvious that the nose-piece and cover may be screwed together or held together by any other well-known means. It will be seen from Fig. 75 2 that the rubber-bulb handle communicates directly with the nose-piece or holder.

13 is a suitable chain or other support by means of which the cap or cover is secured to the telephone.

In Fig. 5 I have illustrated a modified form of cap or cover wherein the cap comprises a plate 14, around which is an annular depend- 80 ing flange 15 of a shape similar to the outline of the mouthpiece of a telephone or other speaking instrument, said plate having an an- 85 nular depressed portion 16, which is provided with suitable perforations 17, said plate 14 being surmounted by a plate 18, the outer edge of which is bent upwardly, then in- 90 wardly, as at 19, thereby forming a groove around the circumference of said plate, the said plate being provided with suitable per- 95 forations 20 and secured to the plate 14 by rivets 21 or other suitable means. 22 is a re- 95 silient bulbous covering the edges of which are firmly secured within an annular groove around the plate 18. 23 represents suitable antiseptic material secured in the space formed between the plates 18 and 14 by the 100 depression 16. It is obvious that the plates 14 and 18 may be secured together in such

manner that they may readily be separated for the purpose of renewing the antiseptic material held between the same.

In Fig. 6 I have shown still another form 5 of cap or cover wherein 24 is a skeleton frame from which project fingers or clamps adapted to be bent around the outside of the mouthpiece of a telephone, thereby securing said frame to said mouthpiece. 25 is a plate hinged 10 at one end to the frame 24 and provided with a central annular depression 26 and perforations 27. 28 is a flat perforated plate secured on top of the plate 25 and bent upward at its edges at 29 to form a groove entirely around 15 the same. 30 is a resilient or bulbous member the edges of which are firmly secured within the groove formed around the edge of the plate 28. 31 is a suitable disinfectant or antiseptic material secured between the 20 plates 28 and 26.

It is evident that the purpose of this device is to prevent the spread of disease by parties using telephones and also to keep the mouthpiece of the telephone or speaking-tube in a 25 clean condition.

In use the cap is attached to the telephone-cabinet by a chain or other suitable means. When it is desired to use a telephone or speaking-tube, the cap is removed by grasping the 30 bulb handle 7, which is compressed by the hand, thereby forcing a body of air through the disinfecting tablet or material, thence through the absorbent cotton, from which it escapes in small jets through the perforations 35 10 as medicated air into and around the inner portion of the mouthpiece, thereby disinfecting the same and killing any germs of disease that may have lodged in said mouthpiece.

The operation of the construction shown in 40 Fig. 5 is substantially like that described with reference to Fig. 2.

In Fig. 6 the cap or cover is not entirely removed from the mouthpiece. When it is desired to use the phone the thumb would be 45 placed under the lower portion of the plate 28, and the fingers of the hand would naturally be placed upon the bulb 30, and in swinging the cover up, as in Fig. 7, the bulb would be compressed by the fingers, thereby 50 automatically forcing a body of air through the perforations in the plate 28 into the disinfecting material 31, from which it passes through the perforations 27 in the plate 26 into and around the inner portion of the 55 mouthpiece, the combined plates 28 and 26 and the bulb 30 being swung back out of the way, thereby leaving the mouthpiece free for use.

It will be noted from the several views of 60 the drawings that the nose-piece or holder projects some distance into the mouthpiece of the speaking instrument, thus insuring a thorough distribution of the medicated air throughout all portions of the said mouth-piece.

The medical fraternity lay a great deal of stress on disease germs being carried or con-

veyed through contact with insects (flies particularly) and also dust, the dust forming a bed or convenient element as a resting-place— 70 not only as a resting-place, but in traveling with the dust when the dust is disturbed or blown out of its corner, as might be the case from a mouthpiece. Thus the excluding of dust, flies, or other insects from such mouth-piece is very essential. 75

I do not wish to limit myself to a removable cover, as I may construct a cover so that instead of removing it a slide or disk could be moved or rotated on the cover, so as to bring 80 the openings in line with one another for the purpose of talking through them.

Having now described my invention, what I claim as new is—

1. In combination with a mouthpiece of a 85 speaking instrument, a removable cap applied to the end thereof, a disinfectant secured in said cap and means for expressing the disinfectant from the cap in the act of removing the cap.

2. In combination with a mouthpiece of a speaking instrument, a cap to cover the same, a perforated receptacle in the cap for holding a disinfectant, a hollow resilient handle secured to the cap and communicating with 95 said receptacle.

3. In combination with a mouthpiece of a speaking instrument, a cover for the same, a holder connected to and removable with the cover and projecting inside of the mouthpiece and containing an antiseptic material or disinfectant and means for forcing said material into the mouthpiece when the cover is removed.

4. In combination with a mouthpiece of a 105 speaking instrument, the removable cover, a disinfectant-holder or nose-piece, removably attached to the cover, and extending into said mouthpiece.

5. In combination with a mouthpiece of a 110 speaking instrument, a removable cover for the same, a nose-piece or holder removably secured to the cover, a lozenge or tablet, containing disinfectant ingredients secured in 115 said nose-piece or holder and means for admitting air to be forced through or around said tablet into the said mouthpiece.

6. In combination with a mouthpiece of a speaking instrument, a cover for the same, a nose-piece or holder removably secured to the 120 cover, an antiseptic material secured in said nose-piece and means for forcing air through or around said antiseptic material into the mouthpiece.

7. A mouthpiece of tubular form for speaking instruments containing a disinfecting or deodorizing tablet or lozenge, so located with reference to the mouthpiece that the tablet when in place is forward of the front edge or inside of the opening to the said mouthpiece. 125

8. The combination, with the cover of a telephone or other speaking instrument; of a hollow flexible handle, and deodorizing material contiguous to the mouthpiece and cover, for 130

the purpose of deodorizing or keeping the mouthpiece fumigated.

9. The combination, with the cover and mouthpiece of a telephone or other speaking instrument; of a hollow flexible handle, and deodorizing material located between the cover and mouthpiece, for the purpose of deodorizing or keeping the mouthpiece fumigated.

10. The combination, with the cover and mouthpiece of telephones or other speaking instruments, of a tablet, or evanescent material, or deodorizing ingredients, and a hollow flexible part carried by the cover, and arranged so that air, gas or fumes, from the tablet, or evanescent material, or deodorizing ingredients may escape or be forced through the cover into the mouthpiece.

11. The combination, with the mouthpiece of a telephone or other speaking instrument,

of a disinfecting or deodorizing tablet, or lozenge formed of such material that it slakes or forms gases by the action of the air and so arranged within the mouthpiece as to permit air to circulate through, over and around said tablet or lozenge.

12. The combination, with the cover for a mouthpiece of a telephone or other speaking instrument; of a disinfecting or deodorizing tablet or lozenge formed of such material that it slakes or forms gases by the action of the air, and so arranged in connection with the cover as to permit the gases or ingredients from the tablet or lozenge to escape into the mouthpiece.
